STOVE BOARD

Stanley F. Jackes, St. Louis, Mo., assignor to
 Jackes-Evans Manufacturing Company, St.
 Louis, Mo., a corporation of Missouri

Application January 21, 1938, Serial No. 186,106

2 Claims. (Cl. 154—45.9)

This invention relates to stove boards, and with regard to certain more specific features, to sheet-insulating stove boards.

Among the several objects of the invention may be noted the provision of stove boards which are effectively heat-insulating so that they effectively protect the floors upon which they rest; and the provision of a stove board of this class which is easy to fabricate rigidly from inherently flexible or bendable sheet metal and which may be sold at a low price. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawing, in which is illustrated one of various possible embodiments of the invention,

Fig. 1 is a perspective view showing the top of my new board;

Fig. 2 is a view similar to Fig. 1, but showing the bottom of the board;

Fig. 3 is a vertical section taken on line 3—3 of Fig. 1; and,

Fig. 4 is a vertical section taken on line 4—4 of Fig. 1.

Similar reference characters indicate corresponding parts throughout the several views of the drawing.

Stove boards of the class herein referred to are made for supporting stoves, and have for their purpose the protection of the floor therebeneath. The protection is against scorching by radiation from the stove, dropping of hot ashes, and the like. Previously, stove boards have been made, sometimes merely out of metal. These have not been very effective, because metal is a good transmitter of heat.

Some metal stove-boards have previously been backed with asbestos, paper, or with wood. These have been expensive and not always rigid enough.

Referring now more particularly to Fig. 1, there is shown at numeral 1 a top layer of normally flat sheet metal in which may be impressed any suitable decorative design, such as the block figure shown. This sheet metal, although inherently flexible or bendable, remains substantially flat after being impressed and organized with a backing, as hereinafter described. Behind or beneath the sheet metal is a normally flat gypsum wall-board or plaster board 3, over the

edges of which the edges of sheet metal 1 are clinched as at 5. The clinch is formed by an elevated portion 7 which serves not only decoratively to set off the edge of the top 1, but prevents the direct transmission of edge blows 5 against the board 3. Corner cleats are shown at numerals 9, but it is to be understood that these may be dispensed with and form no new part if this invention.

The normally flat gypsum wall-board 3 comprises a central gypsum or like, inherently rigid monolithic layer 11 above which is an enclosing layer of cardboard 13, and below which is another enclosing layer of cardboard 15. The cardboard layers 13 and 15 serve to contain the frangible gypsum layer and are solidly adhered thereto thus making a preformed normally flat insulating structure. The wall board remains substantially flat during the use for which it is herein indicated, and prevents the inherently bendable or flexible sheet metal from deviating downward from its normally flat condition.

The gypsum 11 is fireproof, and it will be understood that any other similar fireproof plastic material which will become monolithic may be used. As is known, the gypsum is plastic when wet and dries into a monolithic frangible mass when dry, the containing layers 13 and 15 adhering thereto.

The nature of the paper layers is fibrous, and this fact accounts for improved strength in the monolithic gypsum layer. It also strengthens the frangible gypsum against breakage, and holds together various sections of it, even if it should crack. The upper layer cushions against local deflections that may occur in the sheet metal 1.

The term wall board is used herein as meaning a normally flat sheet of material of rigid enough construction to form a wall-like structure. It is of the type wherein the monolithic layer between the fibrous layers is adhered to the latter to form an organized, unitary and flat structure.

The term plaster board herein means a board whose rigidity depends upon a layer of a substance which is plastic when wet and a hard and normally flat monolith when dry.

It will be noted that, except for the clinching portions 5, the metal layer 1 and the board 3 are unattached. They remain coplanar because of their normally flat characteristics.

In view of the above, it will be seen that the several objects of the invention are achieved and other advantageous results attained.

As many changes could be made in carrying out the above constructions without departing

from the scope of the invention, it is intended that all matter contained in the above description or shown in the accompanying drawing shall be interpreted as illustrative and not in a limiting sense.

I claim:

- 5 1. A stove board comprising a top layer of normally flat but inherently bendable sheet metal, a bottom layer comprising an initially separate, rigid and flat plaster board, said board comprising as a preformed unitary organization a flat monolithic layer of a frangible plaster-like substance such as gypsum, a cardboard-like protecting layer attached to said plaster-like layer and located between it and said top metal layer, and a cardboard-like layer attached to said plaster-like substance and located below the same, the edges of said sheet metal being clinched over the edges of said plaster board, the two cardboard-

like levers protecting the relatively frangible plaster-like layer against breakage at the clinch and against breakage by local deflections in the top layer and holding together any separate portions of the plaster-like layer should it crack. 5

- 10 2. A stove board comprising a top layer of normally flat but inherently bendable sheet metal, a bottom layer comprising an initially separate, rigid and flat plaster board, said board comprising as a preformed unitary organization a flat monolithic layer of a frangible plaster-like substance such as gypsum, a cardboard-like protecting layer attached to said plaster-like layer and located between it and said top metal layer, the cardboard-like layer protecting the relatively 15 frangible plaster-like layer against breakage by local deflections in the top layer.

STANLEY F. JACKES.
